UNITED STATES PATENT OFFICE

107,262

DESIGN FOR A SMOKER'S ASH STAND

Jacob I. Russakov, Chicago, Ill.

Application January 21, 1937, Serial No. 67,174

Term of patent 7 years

To all whom it may concern:

Be it known that I, Jacob I. Russakov, a citizen of the United States, residing in Chicago, Cook County, Illinois, have invented a new, original, and ornamental Design for a Smoker's Ash Stand, of which the following is a specification, reference being had to the accompanying drawing forming a part thereof.

The figure is a perspective view of a smoker's ash stand showing my new design.

The characteristic features of the design reside in the combination of the bridge member and receptacle of the specific configurations shown, said bridge member being of a color contrasting

with that of the receptacle and relatively large and substantially square in cross section and having a central bearing member with vertically projecting portions terminating in relatively square end portions corresponding with the end portions of the bridge member and having a plunger element passing through the bearing member and terminating in a mushroom shaped handle portion of a color corresponding with that of the bridge member.

I claim:—

The ornamental design for a smoker's ash stand, substantially as shown and described.

JACOB I. RUSSAKOV.
